John P. Williams, Inventor,
By his Attorney, J. H. Littell,

UNITED STATES PATENT OFFICE.

JOHN P. WILLIAMS AND HERMANN HUHN, OF NEW YORK, N. Y., ASSIGNEES TO
ELECTRIC BANK PROTECTION COMPANY, A CORPORATION OF DELAWARE.

ELECTRICALLY-PROTECTED GRILLE-WORK OR GRATING.

1,027,679.

Specification of Letters Patent. Patented May 28, 1912.

Application filed December 8, 1910. Serial No. 596,267.

To all whom it may concern:

Be it known that we, JOHN P. WILLIAMS and HERMANN HUHN, both citizens of the United States, and residents of New York, in the county and State of New York, have invented certain new and useful Improvements in Electrically-Protected Grille-Work or Gratings, of which the following is a specification.

10 This invention relates to that class of electrically-protected grille-work or gratings which are adapted for use at or in doors, windows or other openings of a building or structure to be protected, and which operate, 15 when an attack is made upon their parts, to close an electric circuit and cause an alarm to be given.

Our improvements are adapted for effective use upon any structure to be protected, 20 or in the construction of prison cells to prevent prisoners from making escape without giving an alarm, or the invention may be applied to the doors and windows of a prison for a like purpose.

25 The object of our invention is to provide an improved protective grille-work or grating which will be operatively effective against an attack by either bending, clamping or cutting the bars, and which will furthermore possess advantages in point of 30 simplicity, strength, positive operation and general efficiency.

The component parts of our invention are assembled, and electrical connections made, 35 in such a manner that an attack in any way disturbing the normal status of the construction, to secure entrance therethrough, especially by bending, clamping, or cutting the bars, will cause an electric circuit to be instantaneously closed and an alarm given.

40 A structure composed of our electrically-protected grille-work or grating may be built to surround any object to be protected, such as a safe or vault or storage compartment.

45 In the drawings—Figure 1 is an elevation, showing our improved electrically-protected grille-work or grating applied to a window opening of a building and arranged to obstruct said opening and prevent passage

therethrough. Fig. 2 is a vertical section, taken on the line $x-x$ of Fig. 1. Fig. 3 is a horizontal section, taken on the line $y-y$ of Fig. 2. Fig. 4 is a vertical section of a modified form of construction. 55

Corresponding parts in all the figures are denoted by the same reference characters.

Referring to the drawings, our electrically-protected grille-work or grating is shown at Δ , applied to a window opening, 60 B, of a building, C.

The improved grille-work or grating, in the type of construction herein shown, comprises top and bottom supporting bars or members, 1 and 2, and vertical bars or members, 3, the parts of the structure being assembled and electrified in such a manner that an alarm circuit, forming a part thereof, will be operated to sound an alarm in case an effort is made to gain entrance 70 through the structure by bending, clamping, sawing, cutting or otherwise attacking the same. The top and bottom supporting members 1 and 2 are similar in construction and are composed of outer and inner channel members, 4 and 5, spaced apart throughout and insulated one from the other, said channel members being of metal or other conducting material. The outer channel members 4 consist of central webs, 6, having apertures, 7, and spaced flanges, 8, over which caps or covers, 9, are placed and secured. This construction provides chambers, 10, in which are housed the inner channel members 5, which comprise central webs, 11, having apertures, 12, therein and spaced flanges, 14, 85 thereon.

The vertical bars or members 3 of the structure are of metal or other conducting material and comprise outer tubular bars, 90 15, preferably reduced at the ends thereof, as at 16, to snugly fit into the apertures 7 of the webs 6 of the outer channel members 4, and inner bars, 17, spaced from the tubular bars 15 throughout and insulated therefrom by sleeves, 18, of fiber or other insulating material which are seated over the ends of the inner bars 17 and in the ends of the outer tubular bars 15, as shown in Fig. 2. The insulating sleeves 18 are pro- 95 100

vided with annular flanges, 19, which, when the parts are relatively assembled, lie between the central webs 6 and 11 of the outer and inner channel members 4 and 5 respectively, and insulate one from the other. The inner bars 17 may be solid, as herein shown, or they may be tubular if desired. The ends of said bars 17 are threaded, as at 20, and are passed through the apertures 12 in the webs 11 of the inner channel members 5, and nuts, 21, are screwed home on said threaded ends to securely bind the structure together, as will be readily understood. Cross pins, 22, are provided transversely at one end of the inner bars 17 (or at both ends, if desired), for the purpose of making contact with the spaced flanges 8 of the outer channel member 4, to close an alarm circuit, should the inner bar 17 be rotated by the action of a saw, file or other instrument in an attempt to sever the same.

The structure above described is preferably composed entirely of conducting material, except the insulating sleeves 18.

In the preferred electrical circuit arrangement, the outer and inner channel members 4 and 5 are respectively connected, as at 23 and 24, to the positive and negative terminals of an alarm circuit, 25, adapted to be closed and operated when the insulated parts of the structure are brought into contact by bending or clamping or should a saw, file or other instrument be used to cut, or sever or drill through the vertical bars or members or should any such attack be made upon the supporting bars 1 and 2, as will be readily understood. Included in the alarm circuit arrangement is an automatic drop, 26, controlled by a magnet, 27, an alarm gong or device, 28, and the usual battery, 29. Thus, in the operation of our improved electrically-protected grille-work or grating, if in an attack upon the structure any one of the outer tubular bars should be bent or distorted into contact with the inner bars, a circuit will be established through the outer tube 15, outer channel member 4, a conductor, 30, the battery 29, a conductor, 31, the magnet 27, a conductor, 32, the inner channel member 5 and the inner rod 17. The closing of this circuit energizes the magnet 27 and causes its armature hook, 33, to release its contact bar, 34, allowing it to contact with a contact point, 35, of a local alarm circuit, 36, and a closed circuit is established through a conductor, 37, the alarm gong 28, a conductor, 38, the battery 29, the conductor 31 and the contact bar 34, and this circuit remains closed and the alarm will be actuated until the contact bar 34 is manually reset in normal position.

The flanges 14 of the inner channel members 5 are, in the preferred construction, cut away, as at 39, to allow the pins 22 carried by the inner bars 17 to pass when the inner

bars 17 are rotated, the contact of the pins 22 being made with the flanges 8 of the outer channel members 4 to close the alarm circuit.

In the modified construction shown in Fig. 4, a revoluble bearing is provided for the inner bars 17. Said bearing preferably comprises a bearing member, 40, secured upon the threaded end of the inner bar 17 and seated over the central web 11 of the inner-channel-member 5, and balls, 41, interposed between the web 11 and an annular groove or race, 42, provided in the face of the block or member 40. With this construction should an attack be made by cutting the bars with a saw or file and the outer bar 15 is penetrated, the cutting instrument will come in contact with the inner bar 17, and then cause the rotation thereof without severance, and the pin 22 carried by the inner bar will immediately contact with the flanges 8 of the outer channel member 4 and close the alarm circuit, or as above set forth the circuit may be closed directly through the contact of the cutting instrument with the outer and inner bars 15 and 17.

It will be understood that our improved grille-work or grating may be effectively employed either in vertical or horizontal position, and that any suitable additional mechanical supports may be placed between the bars 15 to brace them in relative position.

We do not desire to be understood as limiting ourselves to the detail construction and arrangement of parts as herein shown and described, as it is manifest that variations and modifications therein may be resorted to, in the adaptation of our invention to varying conditions of use, without departing from the spirit and scope of our invention and improvements. We therefore reserve the right to all such variations and modifications as properly fall within the scope of our invention and the terms of the following claims.

Having thus described our invention, we claim and desire to secure by Letters Patent:

1. An electrically-protected grille-work or grating comprising an outer tubular bar, an inner bar revolably mounted and extending therein and fixed against longitudinal movement, said inner and outer bars constituting electrical conductors and being normally spaced apart and having exposed surfaces, substantially, throughout their length, supporting means constituted by an outer bar in connection with said tubular bar and an inner member in connection with said inner bar, said outer and inner members of said supporting means constituting electrical conductors, contact means carried by said revoluble bar and operative to con-

taet with said outer bar of said supporting means when said revoluble bar is rotated, and an electrical alarm circuit including said outer and inner members of said supporting means, whereby when said tubular bar or revoluble bar is bent or distorted to bring the exposed surfaces of said bars in contact or the inner revoluble bar is rotated the circuit will be closed to operate the alarm.

10. An electrically-protected grille-work
or grating, comprising an outer tubular bar,
an inner bar revolvably mounted and extending
therein and fixed against longitudinal
movement, said inner and outer bars constituting
15 electrical conductors and being normally spaced apart and having exposed surfaces substantially throughout their length, supporting means constituted by an outer bar in connection with said tubular bar and an inner bar in connection with said revolvble bar, said outer and inner bars of said supporting means constituting electrical conductors, an insulation between said outer
20 and inner bars of said supporting means and between said tubular bar and revolvble bar at the end portion thereof, a lateral projecting member carried by said revolvble bar and operative to contact with said outer bar
25 and of the supporting means when said revolvble bar is rotated, and an electrical alarm circuit including said outer and inner bars of said supporting means, whereby when
30 said spaced bars are bent or distorted to bring their exposed surfaces in contact or
35 the inner revolvble bar is rotated the circuit will be operated to actuate the alarm.

3. An electrically-protected grille-work or grating, comprising an outer tubular bar, 40 an inner bar revolvably mounted and extending therein and fixed against longitudinal movement, said inner and outer bars constituting electrical conductors and being normally spaced apart and having exposed surfaces, 45 supporting means constituted by an outer bar in connection with said tubular bar and an inner bar in connection with said revolvable bar, said outer and inner bars of said supporting means constituting electrical 50 conductors, an insulation extending between said outer and inner bars of said supporting means and between said tubular bar and revolvable bar at the end portion thereof, a lateral member carried by said revolvable bar and operative to contact with the outer bar of said supporting means when 55 said revolvable bar is rotated, a bearing interposed between the inner bar of said supporting means and said revolvable bar, and 60 an electrical alarm circuit including said inner and outer bars of said supporting means.

4. An electrically-protected grille-work or grating, comprising an outer tubular bar, 65 an inner bar extending therein and fixed

against longitudinal movement, said inner and outer bars constituting electrical conductors and being normally spaced apart and having exposed surfaces, supporting means constituting an outer member in connection with said tubular bar and an inner member in connection with said inner bar, an insulation extending between said outer and inner members of said supporting means and between said tubular bar and inner bar 70 75

and between said tubular bar and inner bar at the end portion thereof, a nut carried at the end of said inner bar and clamping the inner member of said supporting means and said insulation in operative position, and an electrical alarm circuit including both said spaced outer tubular bar and inner bar. 80

5. An electrically-protected grille-work or grating, comprising an outer tubular bar, an inner bar revolvably mounted and extending therein and fixed against longitudinal 85

movement, said inner and outer bars constituting electrical conductors and being normally spaced apart and having exposed surfaces substantially throughout their length,

contact means carried by said revoluble bar for closing the circuit connection thereof when said bar is rotated, supporting means inclosing the end of the inner revoluble bar

and its contact means and constituted by an outer member in connection with said tubular bar and an inner member in connection with said revoluble bar, said outer and inner members of said supporting means consti- 95

tuting electrical conductors and being normally spaced apart and having exposed surfaces substantially throughout their length, and an electrical alarm circuit including said

tubular bar and revoluble bar and said outer and inner members of said supporting means.

means.

6. An electrically-protected grille-work or grating, comprising a fixed outer tubular bar, an inner bar extending longitudinally thereto and fixed against swinging or lon-

therein and fixed against swinging or longitudinal movement, said inner and outer bars constituting electrical conductors and being permanently spaced apart and having exposed opposite surfaces substantially 11

exposed opposite surfaces substantially throughout their length, supporting means housing the end portions of said bars and each constituted by an outer member or bar in connection with said tubular bar and an

in connection with said tubular bar and an inner member or bar in connection with said first named inner bar, said inner member or bar extending within said outer member or bar of said supporting means and being

bar of said supporting means and being spaced therefrom substantially throughout its length and said members or bars of said supporting means having exposed opposite faces substantially throughout their 12

surfaces substantially throughout their length and constituting electrical conductors, and an electrical alarm circuit including both said spaced members or bars of the

therein, whereby when said spaced members or bars of the supporting means of said spaced outer tubular bar and the inner bar extending therein are bent or distorted to bring their opposite exposed surfaces in contact the circuit will be operated to actuate the alarm.

In testimony whereof we have signed our

names in the presence of the subscribing witnesses.

JOHN P. WILLIAMS.
HERMANN HUHN.
